UNITED STATES PATENT OFFICE.

EMIL TYDEN, OF CHICAGO, ILLINOIS, ASSIGNOR TO THE INTERNATIONAL SEAL AND LOCK COMPANY, OF HASTINGS, MICHIGAN.

SEAL.

SPECIFICATION forming part of Letters Patent No. 618,146, dated January 24, 1899.

Application filed April 4, 1898. Serial No. 676,438. (No model.)

To all whom it may concern:

Be it known that I, EMIL TYDEN, a citizen of the United States, residing at Chicago, county of Cook, and State of Illinois, have invented certain new and useful Improvements in Seals, which are fully set forth in the following specification, reference being had to the accompanying drawings, forming a part thereof.

- 10 This invention is an improvement in seals designed for sealing bags, pouches, freight-cars, and the like, and it is particularly designed to compel the handling of the seal by the person intrusted with the inspection of 15 the same from time to time in order that any tampering with the seal may be detected; and it consists in such an arrangement of the characters of the identifying-number with which the seal is marked that the entire number 20 cannot be seen without a certain amount of manipulation of the device, which cannot be performed without disclosing the fact that the seal has been tampered with, if such is the case.
- 25 This invention, broadly considered, is shown and claimed in my application, Serial No. 658,158, filed November 11, 1897; but one of the several specific forms of the invention which are shown in that application and not 30 therein claimed is the specific subject of this application.

In the drawings, Figure 1 is an elevation of my improved seal. Fig. 2 is a longitudinal section at the line 2 on Fig. 1. Fig. 3 is a plan of a modified form of the same invention. Fig. 4 is an edge elevation of the structure shown in Fig. 3. Fig. 5 is a plan of a further modification, and Fig. 6 is an edge elevation of the same. Fig. 7 is a plan 40 of a fourth modification, and Fig. 8 is an edge elevation of the same.

In all the forms of seal to which this invention is shown applied in the different figures the general character of the structure is that 45 a strap of flexible material, such as commercial tin, adapted to be inserted through a staple or other fastening of the package or door carries at one end the sealing device or seal proper, and is designed to have the other 50 end inserted through the staple and brought back to connection with the seal-carrying end,

where the two ends are to be retained in connection by the seal, the loop thus formed through the staple being the means of securing the seal in position and preventing the 55 unlocking of the package or door, which can be effected only after rupture of the strap at some point. Although made in one piece, this strap has at its two end portions, it will be seen, two distinguishable functions which 60 might be performed by two separate pieces. The end which is inserted through the staple and afterward joined by the seal to the other part I term the "securing strap or bar," since it is adapted to perform this function when- 65 ever it is at one end prevented from coming through the staple, whether that prevention is due to its integrality and continuity with the other piece which makes it form a loop when folded for junction with the seal-bear- 70 ing end or whether it is effected by any other contrivance at the end corresponding to the loop in the drawings. The other end of the strap I distinguish as the "seal-body-carry- 75 ing strap or bar," since it is adapted to per- 80 form this function regardless of its integral- 85 ity or continuity with the other portion of the strap, and I shall refer to these two portions by these terms, notwithstanding they are por- 90 tions of one piece.

A is the strap, of which the portion A' is the securing strap or bar and the portion A² is the seal-body-carrying strap or bar. The latter is made with a lateral offset-lug A²⁰, which is folded upon itself—that is, so as to 85 overhang the end portion of said bar, as seen in all the views—forming a cleft or guideway a²⁰, through which the end of the securing strap or bar may be passed when the device is sealed. Both sides of this cleft are aper- 90 tured, the apertures being in line through the middle of the cleft to receive the seal B, which may be of soft metal, such as lead, adapted after being inserted through the ap- 95 pertures to be clenched down with a suitable tool at both ends, thus forming a soft rivet, securing the parts together, so that they can- 100 not be separated without destroying at least the head of the rivet, which may receive an identifying-imprint in the process of clenching, by virtue of which it receives the name the "seal." The end of the securing strap

- or bar has an elongated aperture or slot A¹⁰, through which also the seal B passes when it is inserted in position for being clenched or impressed, and the seal thereby prevents the separation of the seal-carrying strap at the seal end of the device; but the elongation of the aperture A¹⁰ in the securing-strap permits a certain range of longitudinal movement of the latter with respect to the seal-carrying strap or bar without permitting the separation of the two parts. Near the position at which the seal is mounted on the seal-carrying bar said bar is offset into the plane of the overhanging lug A²⁰, which bounds the cleft a²⁰, forming a shoulder A²¹, and at a short distance from that point it is again offset in the opposite direction into the original line, forming a second shoulder A²². Apertures a²¹ a²² are formed through the shoulders A²¹ A²², respectively, in line with the cleft a²⁰, and the securing-strap A' is inserted through these apertures on its way into the cleft. The third offset forming the shoulder A²³ and having an aperture a²³ may be made as shown in the forms illustrated in Figs. 3, 4, 5, 6, 7, and 8, and the securing-strap will in such case be secured in all three apertures of all three shoulders on its way into the cleft. It will be seen that with this structure when the seal is clenched through the slot A¹⁰ in the securing-strap a certain portion of one surface of said strap is concealed from view where it lies facing the portion A²⁵ of the seal-carrying strap, and that a portion of the offset surface is similarly concealed by the portion A²⁷ of the seal-carrying strap between the shoulders A²² and A²³. The same fact might be expressed by stating that the securing-strap conceals certain portions of one surface or the other of the seal-carrying straps at the several points indicated—that is, the facing surfaces of the two parts are concealed from view at these points. In each instance also the opposite surface is exposed to view at the same point. Each surface of both parts throughout the extent of these offsets and engagements of the two parts with each other at the apertures in the shoulders is made up of alternately concealed and exposed portions, and by making the length of the slot A¹⁰ in the securing device equal to the length of one of such portions the securing device may be shifted without breaking the engagement at the sealed end sufficiently to interchange the relations of these portions of its surfaces—that is, to conceal at one limit of its movement portions which were exposed at the other limit and to expose those which were concealed.
- In the form shown in Figs. 1 and 2 I have represented as produced and readable on one surface of the securing-strap a succession of characters constituting a serial number, two of which are concealed under the portion A²⁵ of the seal-carrying strap between the shoulders A²¹ A²², one character being exposed between the lug A²⁰ and portion A²⁵ and the

other being exposed beyond the portion A²⁵. The length of the slot A¹⁰ is sufficient to permit the withdrawal of the two characters which are concealed under A²⁵, so that they may be exposed at the right; but such movement will conceal the character which before such withdrawal—that is, while the two first-mentioned characters were concealed—was exposed at the left. At no position, therefore, can the entire seal number be read, and whatever be the position in which the inspector happens to find the parts he must hold the seal-carrying end of the seal and move the securing device longitudinally through it in one direction or the other in order to discover and record all the characters of the number.

In the form shown in Figs. 3 and 4 the third shoulder A²³ is added, and the characters are formed on the opposite side of the securing device from that on which they are shown in Figs. 1 and 2—that is, so that said characters face the surface of the seal-holding or seal-carrying strap as it runs from the left or seal-carrying end, whereas in Figs. 1 and 2 they are on the surface facing away from the other strap at that point. In this form (shown in Figs. 3 and 4) certain characters are concealed by the portion A²⁶ of the seal-carrying strap between the shoulder A²¹ and the seal, and certain other character are concealed by the portion A²⁷ between the shoulders A²² and A²³, the only characters, therefore, which are visible being those which may be seen between the shoulders A²¹ and A²² on the surface of the securing-strap which is facing away from the portion A²⁵. The length of the slot A¹⁰ being, as before, equal to the distance between the shoulders A²¹ and A²² and that being the same as the distance between the shoulders A²² and A²³, the longitudinal movement of the strap A' being equal to the length of the slot, will cause the characters "3 9" which are concealed at A²⁶ to become visible opposite A²⁵, the characters which were first visible at the last-mentioned point being concealed at A²⁷, while the characters which were first concealed at A²⁷ are disclosed beyond the shoulder A²³. The same result is produced here as in the preceding figures—viz., that the movement of the strap in one direction or the other is necessary in order to enable the inspector to discover and record the entire number.

In the form shown in Figs. 1 and 2 it will be noticed that only the characters "2 0 4" are practically involved in the process, because the remaining characters "8 7 5" are never concealed, whereas in Figs. 3 and 4 all the characters "3 9 0 6 4 2" are involved, because none of them are at all times disclosed, but every character is concealed at one position or another. In the form shown in Figs. 5 and 6 three characters only are involved, two of these being placed not on the securing-strap, but on the seal-carrying strap on the inner surface of the portion A²⁵, facing, therefore,

and adapted to be concealed by the securing-
strap running through the shoulders A²¹ A²²,
while the character beyond the body is con-
cealed and disclosed as in the preceding forms.
5 Other characters, as "4 2" and "0 6," may be
added for the purpose of a conveniently large
serial number on the other surface of the seal-
holding strap where they are never concealed,
and an aperture A¹¹ is made in the securing-
strap large enough to disclose one character
only, said aperture being located so that in the
range of movement permitted by the slot A¹⁰,
which in this case is made equal only to the
extent of one figure, said aperture is shifted
15 from one side to the other within the space
between the shoulders A²¹ and A²², so that it
at one limit conceals one and discloses the
other of the two characters borne by the in-
ner surface of the portion A²⁵ between said
20 shoulders, and at the other limit discloses the
second and conceals the first of said charac-
ters. The same generic result, it will be seen,
is obtained in this as in other forms—to wit,
that whatever be the position at which the in-
25 spector finds the parts he must shift the se-
curing-strap in order to ascertain and record
the figure which will be concealed at the first
position.

In the form shown in Figs. 7 and 8 a charac-
30 teristic of the forms illustrated in Figs. 3 and
4 is combined with that illustrated in Figs.
5 and 6—that is to say, all the characters are
involved in the process, the characters at the
right of the seal-body being divided into three
35 groups, one extreme group being in position
to be concealed at A²⁶, while the other extreme
group is in position to be concealed at A²⁷,
where the intermediate group is disclosed at
A²⁵, but the disclosure at A²⁵ is effected after
40 the manner of the disclosure in Figs. 5 and
6—viz., by an aperture A¹¹ in the securing-
strap. Although the figures thus disclosed
through the strap are on the inner face of the
portion A²⁵ instead of upon the outer face of
45 the strap, as in Figs. 3 and 4, it will be ob-
served that the result here attained is pre-
cisely the same as that attained in Figs. 3
and 4.

Other modifications of the same general ex-
50 pedient may be devised; but the four forms
illustrated will sufficiently indicate the prin-
ciple involved. It will be observed that the
mechanical characteristic of all the forms
illustrated is that the two straps or bars which
55 are held in connection by the seal are inter-
laced with each other, so that alternate por-
tions of each are opposed to opposite surfaces
of the other, the interlacing being in such
form as to leave one of the parts practically
60 straight, so that the two parts may have rel-
ative movement longitudinally with respect
to each other through their interlacing points,
and considered in this light it will be seen
65 that the point to which the part A' passes
through the clamp at the end of the part A²
when the seal is fixed is in effect an inter-
lacing point, since between that point and

the point A²¹ one surface of the part A' is ex-
posed and the other surface is concealed by
the part A², precisely as between the other
70 two intersecting points A²¹ A²² or A²² and A²³
in the forms in which an additional bend is
given and an additional intersecting point
afforded.

I claim—

1. In combination with the sealing or lock-
ing device, the two straps or bars which it
retains connected together, such straps or
bars being interlaced, so that successive por-
80 tions of each are opposed alternately to oppo-
site surfaces of the other, one of said parts
having a character on the surface which is
adapted to be thus concealed between the in-
terlacing points, the attachment of the seal
being adapted to permit relative longitudinal
85 movement of the straps sufficient to expose
such character.

2. In combination with the sealing or lock-
ing device, two straps or bars which it retains
connected together, such straps or bars being
interlaced, so that successive portions of each
are opposed alternately to opposite surfaces
90 of the other, one surface of one of the parts
having a character adjacent to one of the in-
terlacing points, the attachment of the seal-
ing device being such as to permit relatively
longitudinal movement of the straps sufficient
95 to shift said character from one side to the
other of such interlacing point, whereby it
may be exposed at one position and concealed
100 at the other position within the range of such
movement.

3. In combination with the seal, the two
straps or bars which it retains connected to-
gether, such straps or bars being interlaced
105 so that successive portions of each are op-
posed alternately to opposite surfaces of the
other, the attachment of the seal being adapt-
ed to permit relative longitudinal movement
110 of the straps, one of them bearing on one sur-
face a serial number or other arbitrary suc-
cession of characters extending past one in-
terlacing point and over a distance greater
115 than the distance between two consecutive
interlacing points, the range of movement
permitted by the seal being less than the longi-
tudinal extent of the serial number; whereby,
at all positions in the range of movement,
120 there are two portions of such serial number,
of which one is concealed and the other is ex-
posed at opposite sides of one of the inter-
lacing points.

4. In combination with the seal, the two
straps or bars which it retains connected to-
gether, such straps or bars being interlaced so
125 that successive portions of each are opposed al-
ternately to opposite surfaces of the other, the
attachment of the seal being adapted to per-
mit relative movement of the straps, one of
130 them having upon one surface a serial num-
ber, which extends past two of the interlacing
points, and over a greater distance than
the sum of two consecutive intervals between
the interlacing points, the range of movement

permitted by the seal being equal to the length of one of said intervals, whereby, at one limit of the range of movement, the two extreme portions of the surface embraced between the limits of the serial number are exposed on opposite sides of the interval between consecutive interlacing points and at the other limit the intervening portion of said surface is exposed.

In testimony whereof I have hereunto set my hand, in the presence of two witnesses, this 26th day of March, 1898, at Chicago, Illinois.

EMIL TYDEN.
